UNITED STATES PATENT OFFICE.

JAMES CLYDE HALDEMAN, OF SALEM, OHIO, ASSIGNOR TO THE SILVER MANUFACTURING COMPANY, OF SALEM, OHIO, A CORPORATION OF OHIO.

ARM-BINDER AND ELEVATING CONTROL-SHAFT LOCK.

1,328,429.

Specification of Letters Patent. Patented Jan. 20, 1920.

Application filed May 2, 1919. Serial No. 294,186.

To all whom it may concern:

Be it known that I, JAMES CLYDE HALDEMAN, a citizen of the United States, residing at Salem, in the county of Columbiana and State of Ohio, have invented a new and useful Arm-Binder and Elevating Control-Shaft Lock, of which the following is a specification.

The invention relates to drilling machines in which an arm for supporting the drill head is carried upon a vertical column and power means is provided for raising and lowering the arm and has more especial reference to means for clamping the arm in adjusted positions upon the column and at the same time locking the raising and lowering means.

In drilling machines of the character above referred to it is a practice to clamp the arm in different positions upon the column and to unclamp the arm when it is desired to raise or lower it upon the column, suitable power propelled means being provided for the raising or lowering of the drill arm. If through carelessness of the operator the power propelled means for raising or lowering the arm is put into motion while the arm is still clamped upon the column considerable damage to the machine will result.

The object of the invention is to provide means for preventing the power propelled means for raising and lowering the arm from being put into operation during the time that the arm is clamped upon the column; to provide means for locking the power propelled means in the inoperative position when the arm is clamped to the column; and to generally simplify and improve drilling machines.

The objects of the invention may be attained by providing in combination with the usual column and drill arm and elevating screw, an elevating control shaft and means for locking said shaft in the inoperative position when the arm is locked to the column.

With these objects in view the invention consists in the novel construction and arrangement of parts, hereinafter described, illustrated in the accompanying drawings, and particularly pointed out in the appended claims, it being understood that various changes in the form, proportions, size and

minor details of construction may be made within the scope of the appended claims, without departing from the spirit or sacrificing any of the advantages of the invention.

The invention thus set forth in general terms is illustrated in the accompanying drawings forming part hereof, in which—

Figure 1 is a side elevation of a drilling machine embodying the invention.

Fig. 2 is a horizontal section on an enlarged scale on the line 2—2, Fig. 1.

Fig. 3 is a detail perspective view of one of the clamping arms.

Fig. 4 is a detail perspective view of one of the clamping plates.

Fig. 5 is a section on line 5—5, Fig. 1.

Fig. 6 is a plan view of the gearing located in the housing at the upper end of the column.

A practical embodiment of the invention is disclosed in the accompanying drawings, forming a part of this specification in which similar numerals of reference indicate corresponding parts throughout the several views.

Referring to the accompanying drawings, the bed of the drilling machine is indicated generally by the numeral 1 and supports the base 2 of the inner column 5^a, the usual arm which carries the drilling mechanism being indicated at 4 as slidably mounted upon the outer column 3 and a base cap 5 being shown upon the outer column above the base portion 2.

A suitable drill head 6 is carried by the drill arm and contains the usual drill spindle 7 which is arranged to carry a drill of any usual and well known construction.

The drill arm is arranged to be moved vertically upon the outer column by means of the usual screw shaft 8 and is provided with the usual clamp bearing 9 about the column for the purpose of clamping the drill arm in adjusted positions upon the column.

The threaded shaft 8 is journaled in a bearing 10 in the base cap 5 and in a bearing 11 in the top 12 of the column, said shaft having threaded connection with a threaded bearing in the arm 4 in the usual manner. Suitable means are provided for rotating the screw shaft in opposite directions accomplished in the present instance

by providing a gear 13 fast upon the upper extremity of the screw shaft 8 within the top or housing 12. An upright shaft 14 is journaled inside of the inner column in the usual manner and is rotated by means of suitable gearing (not shown) operated through the power pulley 15. The pinions 16 and 17 are fast upon the shaft 14, the pinion 16 meshing with the gear 18 which is carried upon a stub shaft 19, a pinion 20 being rotatable with the gear 18. A bell crank 21 is pivoted upon the upper end of the screw shaft 8 and carries a pinion 22 which meshes with the gear 13 and is adapted to be moved into mesh with either the pinion 20 or the pinion 17 this movement being accomplished through the gear segment 23 provided upon one arm of the bell crank and meshing with the pinion 24 which is fast to the upper end of the elevating control shaft 25 which is journaled within a suitable bearing 26 in the housing 12 and a bearing 27 in the collar 5 and is provided with a rock arm 28 by which it is operated.

As above stated the drill arm has a bearing 9 around the outer column which bearing is a clamp bearing and is provided with slots 29 at its upper and lower ends, lugs 30 and 31 being provided at opposite sides of each slot 29. Each lug 31 is provided with a vertical bearing portion 32 having therein a vertical half round groove 33 arranged to receive the elevating control shaft 25.

A clamp screw 34 is located through each pair of bearings 30—31, said screw being screw threaded for a portion of its length at each extremity, an adjusting nut 35 being placed upon the extremity of said screw extending through the lug 30 and a set screw 36 being provided through said lug to hold the clamping screw in any desired adjustment.

An annular enlargement 37 is formed upon the clamping screw intermediate its extremities and arranged to be located within the socket 38 formed upon the outer side of the lug 31. By adjusting the adjusting nut 35 to the desired point and tightening the set screw 36 the proper tension permanently desired upon the clamp bearing 9 about the column may be obtained.

In order to clamp the clamp bearing 9 tightly upon the column in any adjusted position and at the same time clamp the elevating control shaft against rotation a clamping plate 39 is mounted upon the outer extremity of each clamp screw, each clamping plate 39 being provided with an inwardly disposed rib 40 arranged to contact with the lug 31 and with a half round bearing portion 41 which engages the elevating control shaft.

A clamping lever 42 provided with a threaded barrel portion 43 is threaded upon the extremity of each of the clamping screws

and engages the outer surface of the adjacent clamping plate 39. Each of the clamping levers is provided with a stop lug 44 arranged for engagement with a suitable portion of the arm in order to limit the downward movement of the lever.

When the clamping levers 42 are operated to release the clamp bearing 9, upon the arm, and also the elevating control shaft 25, the operating lever 28 may be moved to the right rocking the shaft 25 sufficiently to move the bell crank 21, through the pinion 24 and gear segment 23, a sufficient distance to bring the pinion 22 into mesh with the pinion 20, this being the position of the parts shown in Fig. 6 of the drawing. The gear 13 will then, through the chain of gears above described, be rotated, rotating the screw shaft 8 in the proper direction to cause the arm 4 to move downwardly upon the column 3, the drill carried thereby being operated in the usual manner.

When it is desired to clamp the arm in any adjusted position upon the column the operating lever 28 is rocked to the left to disengage the pinions 22 and 20 thus stopping the rotation of the screw shaft 8. The clamping levers are then moved into the clamping position drawing the lugs 30 and 31 together, tightening the clamp bearing 9 around the column and clamping the elevating control shaft 25 between the bearing portion 29 and the clamping plates 39. This is the position of the parts shown in Fig. 1 of the drawings.

It will thus be seen that it will be impossible to put the elevating and lowering mechanism into operation while the parts are thus clamped as the operating lever 28 which controls the operation of the elevating and lowering mechanism cannot be moved until the clamping levers 42 are moved into the unclamped position.

It will be noted that the clamping and unclamping of the clamp bearing 9 about the column and the clamping plates upon the elevating control shaft are simultaneous, both parts being clamped or unclamped by the same movement of the clamping levers.

When it is desired to elevate the arm 4 the operating lever 28 is moved to the left a sufficient distance to bring the pinion 22 into mesh with the pinion 17, thus rotating the screw shaft 8 in the opposite direction, raising the arm 4 upon the column.

In Fig. 6 is illustrated the means of clamping the outer column upon the inner column, the outer column being arranged to be clamped in any adjusted radial position upon the inner column by means of the column clamp bolt 45, which is constructed similarly to the clamping bolts 34 and is located through the lugs 46 and 47 formed upon the base cap 5 of the outer column. An annular enlargement 48 is formed interme-

diate the extremities of the clamping bolt and designed to be located within a socket 49 formed in the outer face of the lug 47.

Both extremities of the clamp bolt are 5 screw threaded, an adjusting nut 50 being threaded upon one extremity and bearing against the outer face of the lug 46 while the column clamp handle 51 is threaded upon the other extremity of the bolt, a 10 washer 52 being preferably interposed between the clamp handle and the outer surface of the lug 47.

The nut 50 is adjusted sufficiently to draw the lugs 46 and 47 together, tightening the 15 base cap 5 of the outer column 3 upon the inner column 5^a, just sufficiently to allow the outer column to be rotated upon the inner column. In order to clamp the outer column in any adjusted radial position upon the inner 20 column the column clamp handle 51 is operated, drawing the lugs 46 and 47 still closer together and clamping the base cap 5 tightly upon the inner column 5^a. A set screw 53 similar to the set screw 36 shown in Fig. 2 25 is provided in the lug 46 and arranged to bear upon the column clamp bolt 45 to prevent movement of the same after it has been properly adjusted by the adjusting nut 50.

I claim—

30 1. In a drilling machine, a column, an arm slidably mounted thereon, means for vertically moving the arm, a control shaft controlling the arm moving means, a clamp screw for clamping the arm upon the column 35 and a clamping plate upon the clamping screw for simultaneously clamping the control shaft against movement.

2. In a drilling machine, a column, an arm slidably mounted thereon, means for 40 vertically moving the arm, a control shaft controlling the arm moving means, a clamp screw and a clamping lever carried thereby for clamping the arm upon the column and simultaneously clamping the controlling 45 shaft against movement.

3. In a drilling machine, a column, an arm slidably mounted thereon, means for vertically moving the arm, a control shaft controlling the arm moving means, a clamp 50 screw carried by the arm, a clamping plate carried by said screw and engaging the control shaft and a clamping lever upon the clamping screw for simultaneously clamping the arm upon the column and clamping the control shaft against movement.

4. In a drilling machine, a column, a drill arm comprising a split bearing about said column, means for raising and lowering said

bearing upon the column, an elevating control shaft controlling said raising and lowering means, bearings at the respective sides of the split in said bearing, a clamp screw located through said bearings, a half bearing formed upon one of said clamp screw bearings and engaging said control shaft, 65 a clamp plate carried by said screw and engaging the control shaft and a clamping lever mounted upon said screw and engaging said clamp plate.

5. In a drilling machine, a column, a split bearing mounted upon said column, lugs carried by said bearing at respective sides of the split therein, an adjusting screw located through said lugs, an enlarged portion intermediate the extremities of said adjusting screw, one of said lugs provided with a socket to receive said enlarged portion, screw threads upon both extremities of said adjusting screw, a nut upon one end of said adjusting screw and a clamping lever 80 threaded upon the other end of said adjusting screw.

6. In a drilling machine, a column, a drill arm comprising a split bearing, slidably mounted upon the column, means for raising and lowering the drill arm upon the column, a control shaft controlling said raising and lowering means, a second split bearing located around the control shaft, an adjusting screw located through both of said 90 split bearings, an enlarged portion upon said adjusting screw intermediate the split bearings and a clamping lever upon said adjusting screw for simultaneously clamping both of said split bearings.

7. In a drilling machine, a column, a drill arm comprising a split bearing slidably mounted upon the column, means for raising and lowering the drill arm upon the column, a control shaft controlling said raising and lowering means, a second split bearing located around the control shaft, an adjusting screw located through both of said 100 split bearings, an enlarged portion upon said adjusting screw intermediate the split bearings, screw threads formed upon both extremities of said adjusting screw, an adjusting nut upon one screw threaded extremity of the screw and a clamping lever upon the other screw threaded extremity of the 110 adjusting screw for simultaneously clamping both of said split bearings.

In testimony that I claim the above, I have hereunto subscribed my name.

JAMES CLYDE HALDEMAN.
